Thos. D. Hall.

UNITED STATES PATENT OFFICE.

FRED E. GORDON, OF CLEVELAND, OHIO, ASSIGNOR TO THE TAYLOR & BOGGIS FOUNDRY COMPANY, OF SAME PLACE.

PAWL-AND-RATCHET DEVICE FOR CHAIN-PUMPS.

SPECIFICATION forming part of Letters Patent No. 392,266, dated November 6, 1888.

Application filed July 16, 1888. Serial No. 280,113. (No model.)

To all whom it may concern:

Be it known that I, FRED E. GORDON, a citizen of the United States, and a resident of Cleveland, county of Cuyahoga, and State of Ohio, have invented certain new and useful Improvements in Pawl-and-Ratchet Devices for Chain-Pumps, of which the following is a specification, the principle of the invention being herein explained, and the best mode in which I have contemplated applying that principle so as to distinguish it from other inventions.

My invention consists in the improvements hereinafter described and claimed.

15 Referring to the drawings, Figure 1 is a plan view of the well-curb and connecting parts. Fig. 2 is a plan view of the pawl, ratchet, and shaft. Fig. 3 is a view, partly in section and partly in elevation, of the parts 20 shown in Fig. 2, and taken on the dotted line of that figure. Fig. 4 is a side elevation view of the well-curb and rotary apparatus with the cap in position. Fig. 5 is a perspective view of the cap.

25 A is a shaft provided with journals a a'. Said journal a has bearing in the bearing-block b, said journal a' having bearing in the bearing-block b'. This latter bearing-block is provided with the outwardly-projecting horizontal portion c, said portion c being provided with the bearing-lugs c', in which the journals d' of the pawl d have bearings. Said pawl is composed of four portions, the upper engaging angular extremity, e, the journals d', 30 the lower weight portion, e', and the shank portion e'', intermediate of the weight and engaging portions and angular to the latter. The angular formation of the shank and weight portion of the pawl relative to the engaging portion causes the latter to be held in close engagement with the teeth of the ratchet-wheel.

35 Cap F is composed of the journal-cap portion f, that fits over the shaft-journal, and outer portion, f', that incloses the ratchet wheel and pawl, said outer portion provided with the circular depressions f'', in which the upper portions of the journals d' respectively fit. Lugs g, formed on either side of the journal-cap 40 f, respectively fit in corresponding openings g', formed on either side of the bearing-block

b', and serve to prevent cap F from moving or slipping when placed in position. On the outer side of the ratchet is the unbroken disk h, integral with shaft and ratchet, that serves to keep 55 the pawl from slipping sidewise off the ratchet, and also serves, by engagement with the inner side of the ratchet-cover, to prevent the shaft from moving endwise.

The cap is of great utility in protecting the 60 journal, ratchet, and pawl from exposure to the elements and without the necessity of extending the upper portion of the well-curb over the entire shaft and connections. The double journaling of the pawl is also a point 65 of great utility, as it renders it particularly secure and easy of motion and, together with the weight, insures the certain action of the pawl.

The foregoing description and accompanying drawings set forth in detail mechanism in embodiment of my invention. Change may therefore be made therein, provided the principles of construction respectively recited in the following claims are employed.

75 I therefore particularly point out and distinctly claim as my invention—

1. The combination of shaft A, provided with a ratchet integral therewith, bearing-block b', provided with the outwardly-projecting horizontal portion c, said portion provided with the bearing-lugs c', and pawl d, provided with the angular portion e, engaging with said ratchet, journals d', bearing in lugs c', and lower weight portion, e', substantially 80 as set forth.

2. The combination of shaft A, provided with a ratchet and disk, h, said disk inclosing the side of said ratchet, the periphery of said disk and the apices of the ratchet-teeth lying 90 in the same circumference, bearing-block b', provided with outwardly-projecting horizontal portion c, said portion provided with bearing-lugs c', pawl d, provided with the angular portion engaging with said ratchet, journals d', formed on either side of the ratchet and having bearing in lugs c', and lower weight portion, e', and cap F, composed of journal-cap portion f, fitting over the shaft-journal, and outer portion, f', that incloses the ratchet-wheel and pawl, said outer portion provided 95 with the circular depressions f'', in which the

upper portions of journals *d'* respectively fit, said pawl engaging on one side with the inner wall of the outer cap portion and on the opposite side with disk *h*, whereby it is prevented from transverse displacement, the outer wall of said cap and disk engaging with each other, whereby said shaft is secured against longitudinal displacement, substantially as set forth.

In testimony that I claim the foregoing to be my invention I have hereunto set my hand this 12th day of July, A. D. 1888.

FRED E. GORDON.
